UNITED STATES PATENT OFFICE.

HENRY HERMAN WESTINGHOUSE AND FRANCIS M. RITES, OF PITTSBURG,
PENNSYLVANIA.

STEAM-ENGINE.

SPECIFICATION forming part of Letters Patent No. 393,597, dated November 27, 1888.

Application filed March 17, 1888. Serial No. 267,519. (No model.)

To all whom it may concern:

Be it known that we, HENRY HERMAN WESTINGHOUSE and FRANCIS M. RITES, citizens of the United States, residing at Pittsburg, 5 in the county of Allegheny and State of Pennsylvania, have invented or discovered a certain new and useful Improvement in Steam-Engines, of which improvement the following is a specification.

Our invention relates to compound engines of the Woolf class or type, or that in which an intermediate receiver is not employed, steam being exhausted directly from the high-pressure to the low-pressure cylinder; and its object is to provide an engine of such type having the functions of admission, cut-off, exhaust, and compression effected by a single valve or a coincidently-moving pair of valve-sections, in which intermediate reduction of pressure without performance of useful work shall be obviated, the number of port-governing elements reduced between the high-pressure and low-pressure cylinders, and substantially uniform compression effected in the high-pressure cylinder under all variations of load and for all points of cut-off, thus attaining, by the employment of a simplified construction, which is readily applicable under various structural conditions, a more perfect utilization of steam than has heretofore been practicable, as is evinced by the indicator-cards produced by an engine in accordance with our invention.

To this end our invention, generally stated, 35 consists in the combination of a high and a low pressure cylinder, a distribution valve or valves governing the admission and exhaust of steam to and from said cylinders, and a clearance-chamber or inclosed passage of determined capacity substantially greater than that normal for the traverse of motive fluid, said clearance-chamber being interposed between the high and low pressure cylinders and communicating continuously with the high-pressure cylinder.

The improvement claimed is hereinafter fully set forth.

Practice has demonstrated it to be a desideratum in the economical use of steam not only that cylinder-compression shall be effected, but also that it shall be finally raised

to the degree of the initial pressure at the commencement of the stroke; and to the end of attaining the highest practicable economy and meeting the present requirements of practical service it is necessary not only that means should be provided for effecting the degree of compression above indicated, but also that these means should possess the capacity of performing their functions under each and every grade of expansion and variation of steam-pressure under which the engine may from time to time be operated. Such capacity, or the attainment of such result, is not, so far as our knowledge and information extends, 65 possessed by or resultant from constructions existing or proposed prior to our invention.

In expansion-engines of the Corliss type and others in which compression is controlled by valves independent of those effecting induction and cut-off the compression is constant, and the valve-motion is imperfect in failing to cause the compression to meet the variations of the boiler-pressure. In single-valve automatic simple engines compression 75 varies with variation of cut-off and becomes a function of the load instead of a function of the initial pressure, sometimes rising far above the boiler-pressure with short cut-offs and as far short of it with long ones.

The distinguishing feature of our invention is the provision of a valve which by the same lip admits steam to the low pressure cylinder and exhausts it from the high-pressure cylinder, and which, when cutting off for the low-pressure cylinder, at the same time effects compression for the high-pressure cylinder within a clearance-chamber of comparatively large volume, the same being preferably such as bears substantially the same ratio to that of 90 the high-pressure cylinder as the volume of the latter bears to that of the low-pressure cylinder.

In the operation of an engine in accordance with our invention we cause the terminal compression in the high-pressure cylinder to be independent of load and to vary with boiler-pressure only by commencing high-pressure compression in every case coincidently with the commencement of low-pressure expansion, 100 the variations of pressure at the point of compression in the high-pressure cylinder thereby

compensating the variation of the point of compression in such manner that compression will at all points of cut-off rise to substantially initial pressure, as illustrated by the 5 compression-curve of the series of indicator-cards shown in Fig. 6.

Our improvement provides a single valve-movement—that is to say, a valve or a coincidently-moving set of valves, which valve or 10 valves are so constructed and operated in relation to a clearance-space of determined capacity, which may be located in a valve-chest and port, or two valve-chests and a connecting pipe or passage, or two or more of said members, and which is constantly open to a high-pressure cylinder, together with a variable 15 cut-off mechanism actuating said valve or valves so as to insure practically the same high-pressure compression curve under all loads 20 and at all points of cut-off, and while said curve necessarily varies with the steam-pressure, its terminal in its several variations coincides practically in each case with the initial steam-pressure, waste of steam in filling clearances 25 being thus shown to be avoided. The duty of the valve or portion of the valve governing the high-pressure cylinder is limited to the performance of the functions of high-pressure admission and cut-off, while the valve or portion 30 of the valve which governs the low-pressure cylinder effects the exhaust and compression of the high-pressure cylinder and the admission, cut-off, exhaust, and compression of the low-pressure cylinder. Under these conditions, the entire space between the two cylinders, however included, up to the low-pressure 35 valve or valve-section, is constantly in communication with and serves as a clearance-space for the high-pressure cylinder, and in any modification of the mechanism employed 40 the admission and cut-off of the low-pressure cylinder are respectively effected simultaneously with and respectively correspond with the exhaust and compression of the high-pressure cylinder. Variations of the point of 45 cut-off being similar in each of two cylinders governed by a single valve-movement, whether applied in a simple or a compound engine, we are enabled by the employment of a single 50 valve-movement and the provision of a clearance-space of determined capacity for the high-pressure cylinder of a compound engine, in connection with the variations of pressure at the points of cut-off in the low-pressure 55 cylinder induced by the variations of the corresponding points of cut-off in the high-pressure cylinder, to effect high-pressure compression to initial pressure at each and all points of cut-off. 60 In the accompanying drawings, Figure 1 is a vertical longitudinal central section through a single-acting compound engine, illustrating an application of our invention; Figs. 2 and 3, vertical transverse sections through the 65 same at the lines x x and y y , respectively, of Fig. 1; Fig. 4, a side view, in elevation, of a double-acting tandem compound engine, illus-

trating another application of our invention; Fig. 5, a horizontal longitudinal central section through the cylinders and valve-chests of the same, and Fig. 6 a diagram illustrating the form of indicator curves developed in the operation of an engine constructed in accordance with our invention.

In the instance shown in Figs. 1 to 3, inclusive, our invention is applied in a single-acting compound engine having a preliminary or high-pressure cylinder, 1, and a secondary or low-pressure cylinder, 2, which are secured side by side to the top of a closed crank-case, 5, constituting the bed or support of the engine, and serving also as a tank or receptacle for the lubricating material of the journals and crank-pins of the crank-shaft 4, the journals 50 of which rotate in bearings 41, fixed in the ends of the crank-case 5. The cylinders 1 and 2 are fitted, respectively, with pistons 7 and 8, which are coupled by connecting-rods 9 to the crank-pins of double cranks 10, set oppositely, or with their pins one hundred and eighty degrees apart, on the crank-shaft 4.

Motive fluid is admitted to the high-pressure cylinder 1, exhausted therefrom to the low-pressure cylinder 2, and thence exhausted into the atmosphere or into a condenser by a single distribution-valve, which reciprocates in a valve-chest, 3, provided with nozzles or passages 15 and 11, to which a supply and an exhaust pipe are respectively connected and communicating with the high and the low pressure cylinders by ports 12 and 14. The valve-chest is preferably lined with a bushing, 40, communicating by proper series of ports with the supply and exhaust passages 15 and 11 and the cylinder-ports 12 and 14. The distribution-valve, which in this instance is of the piston type, is composed of a high-pressure section, 38, and a low-pressure section, 39, which are secured upon and reciprocate coincidently with a valve-stem, 16, actuated by an eccentric, 20, which is mounted freely upon the crank-shaft 4, and is varied and adjusted in position relatively to the crank-line, so as to effect variation of the degree of expansion in accordance with variations of pressure or load, 45 or both, by an automatic cut-off governor of any suitable and preferred construction. The governor illustrated, which is mounted upon a supporting-wheel, 25, fixed upon the crank-shaft 4, is similar in construction to that set forth in Letters Patent of the United States No. 384,485, granted to the Westinghouse Machine Company, as our assignee, under date of June 12, 1888; but the same does not in and of itself form part of our present invention, 50 and need not therefore be at length herein described. The valve-stem 16 is connected by a link, 44, to one arm of a bell-crank lever, 45, pivoted in bearings on the low-pressure cylinder 2, the other arm of said lever being coupled 55 by a ball-and-socket joint or equivalent flexible connection to an eccentric-rod, 19, secured to the strap 21 of the eccentric 20.

The distance between the sections 38 and 39

of the distribution-valve and their relation in position and degree of traverse to the port 12 of the high-pressure cylinder are so fixed that the space within the valve-chest bushing 40 5 between the sections 38 and 39, together with that within the port 12, shall constitute a clearance space or chamber, 42, the capacity of which preferably bears substantially the same ratio to the volume of the high-pressure cylinder as that of the latter to the volume of the low-pressure cylinder, and which is continuously in communication with the high-pressure cylinder. The ratio indicated is that which we have found in practice to develop the most 15 perfect results; but it will be obvious that the capacity of the clearance-chamber may be increased or diminished relatively to that recommended by us, although with a corresponding variation from maximum useful effect. 20 Thus, for example, experiment has shown that a clearance-chamber having only twenty-four per cent. of the capacity of the high-pressure cylinder may be employed with a valve which is so set as to cut off at different points in the 25 two cylinders, respectively, compression being in such case commenced later and yet carried to initial pressure; but such construction involves the disadvantage that the valve must be set out of square and the lead on one side 30 increased and on the other side correspondingly diminished.

The valve-section 38 opens and closes the port or series of ports in the valve-bushing 40, communicating with the supply-passage 15, 35 thereby performing the functions of admission and cut-off for the high-pressure cylinder, the cut-off being effected at different points in the stroke of the piston, respectively, in accordance with the variations of position of the eccentric 20 by the governor. The travel of the valve is such that the high-pressure port 12 is continuously open, and hence the exhaust and compression of the high-pressure cylinder are effected independently of the valve-section 38, 40 the duty of which, other than as a boundary of the clearance-space 42, is limited to the functions first above stated. The valve-section 39 effects the opening and closure of the low-pressure port 14, and thereby performs the 45 functions of admission, cut-off, exhaust, and compression for the low-pressure cylinder, and also those of exhaust for the high-pressure cylinder during the period of the stroke in which the low-pressure port 14 is open and the valve-bushing ports of the supply-passage 15 are closed. 50 It will be seen that the closure of the low-pressure port 14 coincidently initiates low-pressure expansion and high-pressure compression. In each case, moreover, the valve-section 39 acts as an end boundary of the clearance-space 42. 55

In operation motive fluid supplied from the passage 15 to the clearance chamber and the

space above the piston 7 of the preliminary or high-pressure cylinder 1 effects the downward movement of said piston at substantially initial pressure throughout the preliminary portion of its stroke at a point in which, regulated by the governor, under existing conditions of load and pressure, the valve-section 38 closes the ports communicating with the passage 15 and cuts off the supply of motive fluid, the remainder of the stroke of the high-pressure piston being effected by the expansion of the motive fluid previously admitted and remaining in the clearance-chamber and high-pressure cylinder. In the farther traverse of the valve the valve section 39 opens the low pressure port 14 and admits the motive fluid contained in the clearance-chamber and high-pressure cylinder to the low-pressure cylinder, which motive fluid effects the preliminary portion of the stroke of the low-pressure piston 3 under compound expansion exerted between the smaller and larger cylinders. The distribution valve has meanwhile 90 commenced its traverse in the opposite direction, in the course of which, at a point regulated by the governor, its section 39 closes the low-pressure port 14, cutting off the supply of motive fluid from the low-pressure cylinder 95 and coincidently closing the clearance-chamber 42, and thereby commencing high-pressure compression. The remaining portion of the stroke of the low-pressure piston is effected under simple expansion—that is to say, by the 100 expansion of the motive fluid inclosed in the low pressure cylinder—the motive fluid inclosed in the high-pressure cylinder and clearance-chamber being meanwhile in and by the upward stroke of the high-pressure piston compressed at its terminal to substantially initial pressure. Further movement of the valve in the same direction effects the exhaust of the motive fluid which has impelled the low-pressure piston and admits motive fluid 105 to the clearance chamber and high-pressure cylinder for the next succeeding stroke of the piston of the latter, such new supply being subject to no reduction of pressure in filling the clearance-chamber, as it meets therein a 110 previous supply of equal pressure, which is utilized in the exertion of such pressure upon the high-pressure piston in the stroke about to be made.

Variations of the grade of expansion in the 120 operation of the engine would under previous practice involve different degrees, respectively, of terminal high-pressure compression, from the fact that greater or less volumes of motive fluid are, proportionately to the lateness or earliness of the cut-off, admitted to the high pressure cylinder, while the compressive action of the piston, being exerted through the same space in each case, is uniform at all points of cut-off. In the practice of our invention we counteract and compensate for such tendency to variation of the degree of terminal compression above or below initial pressure by effecting each and every grade of low-

pressure expansion coincidently with the initiation of high-pressure compression within a clearance space of such volume as has been determined by experimental research to be requisite to admit of the degree of terminal compression being raised to without exceeding that of initial pressure at the commencement of the stroke. Each change of the point of cut off is consequently accompanied by a corresponding change of pressure at the point of initial compression, (which point corresponds with the point of cut-off,) due to the greater or less amount of motive fluid which has been expanded from the high-pressure cylinder into the low-pressure cylinder, so that the later the cut-off and the less the volume of motive fluid on which compression is to be exerted the greater will be the pressure of said volume, and, conversely, the earlier the cut-off and the greater the volume of motive fluid to be compressed the less will be its pressure.

Figs. 4 and 5 illustrate our invention as applied in a double-acting tandem compound engine, the high and low pressure cylinders 1 and 2 of which are secured in line axially upon a bed-plate, 26, their pistons 7 and 8 being fixed upon a common piston-rod, 6, the cross head of which is coupled by a connecting-rod to the pin of a crank on the shaft 4 in the usual manner. The ports 12 and 12^a of the high-pressure cylinder 1 are governed by a distribution-valve, 38, reciprocating in a valve-chest, 3, to which the steam-pipe 15 is connected, and the ports 14 and 14^a of the low-pressure cylinder 2 are governed by a distribution-valve, 39, working in a valve chest, 3^a. The valves 38 and 39 are simultaneously operated in and throughout their traverse in each direction, the stems 16 and 16^a, to which they are respectively secured, being coupled to a rocker-arm, 19^a, which is in turn connected to the eccentric-rod 19. The eccentric which operates the valves is mounted adjustably upon the crank-shaft, and is, as in the former instance, varied and controlled in position by an automatic cut-off governor carried by a supporting wheel or case, 25, fixed upon the crank shaft.

The valve 38 of the high pressure cylinder is composed of three pistons, *a b b*, connected at suitable distances one from the other to the valve-stem 16, the central piston, *a*, controlling a port or series of ports, 12, through which steam is admitted from the steam-supply pipe 15 to the valve-chest, and the end pistons, *b b*, which are of the same diameter as the central piston, *a*, having no valve function proper, and serving merely to prevent variation of pressure upon opposite sides of the central piston from acting on the governor. The valve 39 of the low-pressure cylinder is composed of four pistons, *d d e e*, secured upon the valve-stem 16^a, the intermediate pistons, *e e*, governing ports or series of ports communicating with the induction and excretion ports 14^a, leading from the valve-chest to the ends of the low-pressure cylinder 2, and a port or series

of ports, 14, leading to the exhaust-pipe 11. The end pistons, *d d*, act similarly to those *b b* of the high-pressure valve, having no valve-function proper--that is, as to port opening and closure—and being provided to prevent variations of pressure on the outer sides of the center pistons, *e e*, from reacting on the governor. The valve-chests 3 and 3^a are connected by low-pressure steam-supply pipes 15^b and 15^a, each of which communicates at one end with constantly-open ports in the valve-chest 3 of the high-pressure cylinder and at the other with ports in the low-pressure valve-chest 3^a, which, when uncovered by one of the valve pistons *e e*, lead into the ports 14^a of the opposite ends of the low-pressure cylinder. The end spaces beyond the valve-pistons *b b* and *d d* in the valve-chests 3 and 3^a may be open to the atmosphere or exhaust-pipe or be connected in each chest by a communicating pipe.

The high and low pressure valves 38 and 39 are coincidently operated by the eccentric-rod 19 and rocker-arm 19^a, and the point of cut-off is, as heretofore, varied by the adjustments of the eccentric effected by the governor. The clearance chamber is in this instance made up of the spaces within the ports of the cylinder and valve-chest and low-pressure supply-pipes and between the end and central pistons of the high-pressure valve and end and intermediate pistons of the low-pressure valve. It will be seen that, as in the former case, said chamber is continuously in communication with the high-pressure cylinder, and that the high-pressure valve performs the functions of admission and cut-off only, those of high-pressure exhaust and compression and of low-pressure admission, cut-off, exhaust, and compression being performed by the low-pressure valve.

The diagram Fig. 6 illustrates a series of three superposed indicator-cards, *x y z*, according substantially with cards taken under different degrees of expansion, respectively, from an engine constructed in accordance with our invention. It will be seen that the points of cut-off correspond in the two cylinders, and that as the pressure at the beginning of high-pressure compression changes the point at which compression begins also changes in such manner that compression reaches and terminates at the same point—*i. e.*, at substantially initial pressure for each of the several points of cut-off.

From the instances herein exemplified it will be apparent that the structural features and conditions of the application of our improvement may be modified in various particulars, in the discretion of those skilled in steam-engineering practice, without departing from the spirit and governing principle of our invention, and we do not therefore limit ourselves to the specific construction herein described and shown, mechanical equivalents therefor, when similarly combined and co-operating correspondingly to effect the result at-

tained by our invention, being considered by us to be within its proper and legitimate scope.

It will be further obvious that our invention is, without departure from its governing principle or substantial change of structural elements, applicable in engines of more than one expansion, as well as in the single-expansion engines selected for illustration.

10 We are aware that compound engines have been heretofore proposed having valves whose distribution functions are similar to those of our own, as herein described, and we disclaim therefore, broadly, a valve of such character.

15 We are further aware that in said engines a port and valve - chest space sufficient to admit of the passage of steam from the high to the low pressure cylinder has been provided, and that said space has been maintained

20 in communication with the high-pressure cylinder. We are not, however, aware of any construction in which said space has been made of determined capacity in the sense in which we employ that term—that is to say, of

25 substantially greater capacity than that which will properly suffice for the traverse of steam or so as to constitute a clearance-chamber of capacity sufficiently great to permit of compression to boiler-pressure and prevent compression above boiler-pressure—nor are we aware of a construction in which a valve performing distribution functions similar to those herein described has been combined with a clearance-chamber, as above set forth, and

35 with a variable expansion-gear, whereby the degree of compression attained by us may be effected under any and all conditions of load and boiler-pressure.

The method of distributing motive fluid for the practice of which our improvement is designed and specially adapted is not claimed as of our present invention, the same being fully set forth in a separate application, Serial No. 285,801, filed by us September 19, 1888.

40 45 We claim as our invention and desire to secure by Letters Patent—

1. In a compound engine, the combination, substantially as set forth, of a high and a low

5c pressure cylinder of different volumes, respectively, a valve or coincidently-operated set of valve-sections effecting the distribution functions of said cylinders, and a clearance-chamber of determined volume substantially greater than that required to serve as an avenue for the passage of motive fluid, said clearance-chamber being interposed between the cylinders and communicating continuously with the high-pressure cylinder.

2. In a compound engine, the combination, substantially as set forth, of a high and a low pressure cylinder of different volumes, respectively, a valve or coincidently-operated set of valve-sections effecting the distribution functions of said cylinders, a variable cut-off mechanism coupled to and actuating said valve, 60 and a clearance-chamber of capacity sufficiently great to permit (at all points of cut-off and variations of boiler-pressure) of compression to initial pressure, said clearance-chamber being interposed between the cylinders and 65 communicating continuously with the high-pressure cylinder.

3. In a compound engine, the combination, substantially as set forth, of a high and low pressure-cylinder of different volumes, respectively, a valve or coincidently-operated set of valve-sections effecting the distribution functions of said cylinders, a variable cut-off mechanism coupled to and actuating said valve, and a clearance chamber or passage of 75 substantially the same ratio in capacity relatively to the high-pressure cylinder as that of the high-pressure cylinder to the low-pressure cylinder, said chamber being interposed between said cylinders, and being continuously 80 open to the high-pressure cylinder.

In testimony whereof we have hereunto set our hands.
